UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,930, dated November 28, 1893.

Application filed October 14, 1893. Serial No. 488,179. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of an arrangement of ornamental scrolls and leaves forming a series of 10 connected ornaments arranged at regular distances apart with oval shaped figures formed of a series of small circles or balls as represented in the accompanying drawing. The border or upper portion of the design is formed 15 of similar ornamental scrolls and leaves forming ornaments, with festoons of small ornaments and balls or circles connecting said ornaments and an oval shaped figure composed of small circles or balls hanging from said

festoons as shown in the drawing. An ornamental band composed of light parallel lines with oval-shaped figures formed of small circles or balls and vertical rows of small balls or circles between said oval figures in the center of said band, forms the base or bottom of 20 25 said border as shown.

What I claim is—

1. The design for wall paper herein shown and described.
2. In the design for wall paper, the border 30 herein shown and described.

Witness my hand this 10th day of October, 1893.

CHARLES BOOZE.
